UNITED STATES PATENT OFFICE.

JOSEPH M. REAMS, OF PUNXSUTAWNEY, PENNSYLVANIA.

WRENCH FOR WIRE-SPOKE NIPPLES.

1,247,328.

Specification of Letters Patent. Patented Nov. 20, 1917.

Application filed January 17, 1917. Serial No. 142,906.

To all whom it may concern:

Be it known that I, JOSEPH M. REAMS, citizen of the United States, residing at Punxsutawney, in the county of Jefferson and

5 State of Pennsylvania, have invented certain new and useful Improvements in Wrenches for Wire-Spoke Nipples, of which the following is a specification, reference being had to the accompanying drawings.

10 This invention relates generally to wrenches and particularly to wrenches peculiarly designed for unscrewing the nuts or nipples on the spokes of wire wheels.

In wire wheels, the spokes are operationally engaged with the hub and at their outer ends have screw-threaded engagement with screw-threaded nipples which extend through the rim to tighten the spokes. Inasmuch as the spokes are very close together, 15 it is difficult to use an ordinary wrench or use pliers for the purpose of unscrewing or screwing up the nipples and one object of my invention is to provide a nipple wrench of such construction that it may be used in 20 these confined spaces.

Again where ordinary wrenches or pliers are used for the purpose of screwing up or unscrewing these nipples, the plier or wrench has to be removed from the nipple 25 after each partial rotation so as to take a new hold at a new place because of the fact that the wrench cannot be rotated within the space between two adjacent spokes and, therefore, a further object of my invention is 30 to provide a wrench which will grip the nipple or grip the spoke so tightly that the wrench will be held in place on the spoke and nipple so as to permit the hand to be removed and a new hold taken on the 35 wrench after a certain rotation thereof.

A further object of the invention is to 40 provide a wrench of this kind which may be forced upon a nipple which has had its facets damaged and still another object is 45 to provide a wrench so designed that it may be used to rotate the nipples of the two spokes adjacent the valve stem which projects through the rim of the wheel.

Other objects will appear in the course 50 of the following description.

My invention is illustrated in the accompanying drawings, wherein

Figure 1 is a perspective view of one form 55 of my wrench showing it in applied position for the removal of a nipple,

Fig. 2 is a longitudinal sectional view of the wrench in applied position;

Fig. 3 is a section on the line 3—3 of Fig. 2;

Fig. 4 is a section on the line 4—4 of Fig. 2;

Fig. 5 is a side elevation of another form of wrench embodying my invention;

Fig. 6 is a face view thereof looking toward the ends of the legs;

Fig. 7 is a section on the line 7—7 looking 65 in the direction of the arrow;

Fig. 8 is a longitudinal sectional view of another form of wrench;

Fig. 9 is an inside face view thereof; 70

Fig. 10 is a longitudinal sectional view of still another form; and

Fig. 11 is a face view thereof.

The form of my device shown in Fig. 1 comprises a strip of metal 10 preferably 75 about $\frac{1}{8}$ of an inch thick and relatively narrow. This strip is longitudinally slotted intermediate its ends as at 11. At one end the strip is formed with a longitudinally extending tapering open-ended slot 12 and at its 80 other end with a relatively shorter tapering open-ended slot 13. The strip is bent upon itself intermediate its ends as at 14 and the ends of the strip are rebent as at 15 and 16. There is thus formed two legs or terminal portions 15 and 16, one relatively short and the other (16) relatively long. The leg or terminal portion 15 forms the wrench proper under most circumstances, that is it is the slot 13 in this leg which is intended to 90 engage the nipple b. The portions 14 and 16 constitute together the handle whereby the wrench may be rotated upon the spoke a.

In practical use the wrench is disposed 95 on the spoke a as in Fig. 1 with the spoke extending through the several slots 11, 12 and 13 and the walls of the slot 12 (or the walls of the slot 13) engage with the many sided head of the nipple b. The wrench may then be rotated on the spoke to unscrew or screw up the nipple. It will be seen from Fig. 3 that the slot 11 is very slightly inclined to or offset from the slots 12 and 13 so that the spoke is slightly deflected or flexed when the wrench is disposed upon the spoke and this causes the wrench to bind on the spoke so that it will not fall off but will remain in any rotated position on the spoke. Thus it is not necessary to remove the wrench after the nipple 110

has been turned a certain degree but the hand of the operator is simply removed from the wrench and then replaced and another turn given to the wrench. This is obviously particularly convenient under the circumstances and it will be seen that the handle of the wrench has practically a three-point bearing on the spoke. Furthermore it will be seen that as the slots 12 and 13 are tapering, they will engage with nipples varying somewhat in diameter, and furthermore that they will wedge upon the nipples. This permits the slotted end of the wrench to be forced on a nipple which has become damaged or worn and permits the wrench to be driven onto the nipple by blows of a hammer, and under these circumstances the side walls of the slot 13 or the slot 12 will form new flat sides on a worn nipple. It will further be seen that inasmuch as the wrench as a whole tapers from the relatively long leg 16 to the relatively short leg 15, the device accommodates itself to the form of the space between two or three adjacent spokes of the wheel.

In Fig. 5 I show another form of my invention which is equally advantageous and which embodies the same principle as the form shown in Fig. 1. This second form also consists of a strip of metal 17 which is bent at its ends to form a relatively long leg 18 and a relatively short leg 19. The leg 18 is formed with a tapered open-ended slot 20 and the leg 19 is formed with a tapered open-ended slot 21. The strip of metal is longitudinally slotted and then the two halves of the strip on each side of the slotted portion are bent in opposite directions as at 22 and 23, so as to form a handle whereby the wrench may be rotated and so that the portion 23, which is slightly inclined to the slots 18 and 19 or offset with relation to the centers of the slots 18 and 19, will bear against the spoke and afford with the wall of the slot 21 a three-point bearing holding the wrench from accidental rotation. The operation of this second form of wrench is precisely the same as that of the form illustrated in Fig. 1.

In Fig. 8 I show another form of wrench embodying the same principle and this wrench comprises a strip of metal 24 bent so as to form a relatively long leg 25 and a relatively short leg 26, the short leg having a tapered open-ended slot 27 and the long leg a tapered open-ended slot 28. In order to provide for the three-point bearing upon the spoke, I strike out from the body of the strip 24 a tongue 29 which tongue is bent downward and then upward so that it intersects a line intersecting the inner ends of the slots at two points. It will be noted, both in Figs. 3 and 5 that the loop 14 and the loop 23 intersect at two points a line drawn from the inner ends of the slots.

In Fig. 10 I illustrate another form which is simpler than the forms previously described but which does not have the three-point bearing on the spoke and, therefore, must depend for its holding power upon being wedged onto the spoke and nipple. In this construction the strip of metal is angularly bent so as to form the legs 33 and 34. The leg 34 is formed with the tapered slot 35 and the leg 33 with the tapered slot 36. This form of wrench is operated in precisely the same manner as the forms previously described.

To all who are engaged in the repair of bicycles, motorcycles and certain forms of automobiles, the need of a wrench of the character described is obvious, particularly in view of the necessity of removing an ordinary wrench from engagement with the nipple after the nipple has been turned a certain predetermined amount. It will be seen that my wrench is very cheaply made, very convenient in use and it has been found thoroughly effective in practice.

Having described my invention, what I claim is:

1. A wrench comprising a body formed of a strip of metal bent to provide legs projecting in the same direction, both of said legs having tapering inwardly extending open-ended slots, the middle of the strip being formed to provide a portion intersecting a line connecting the inner ends of the slots, and said portion being disposed in a plane slightly offset from the plane of the slots and being laterally unyielding.

2. A wrench comprising a body formed with members projecting in the same direction, both of said members having tapering inwardly extending open-ended slots, the slots being disposed in parallel planes, the middle of the body having a portion intersecting a line connecting the inner ends of the slots, the edge of said portion being slightly offset from the plane of the slots.

3. A wrench comprising a body formed of a strip of metal, the ends of the strip being formed with a long slot and a short slot respectively extending longitudinally of the strip, both of said slots being inwardly tapered, the strip being bent to provide a relatively long leg at the end having the long slot and a relatively short leg at the end having the short slot, the middle portion of the strip being formed to provide a portion bent in the direction of the legs and intersecting at two points a line connecting the inner ends of the slots, the edge of said portion being slightly offset from the plane of the slots.

4. A wrench comprising a strip of metal bent to provide two legs at its ends, extending in the same direction, one of the legs being longer than the other, and to provide an intermediate portion bent in the direc-

tion of the legs, the edge of this intermediate portion intersecting at two points a line connecting the inner ends of said slots and being slightly offset from the plane of 5 said slots.

5. A double ended nipple wrench having ends bent to form a hammering or driving part at each end, said ends having respectively long and short inwardly extending, 10 uniformly tapering slots, the middle por-

tion of the wrench being formed with a spoke engaging part designed to frictionally engage a spoke or other element and being laterally unyielding.

In testimony whereof I hereunto affix my 15 signature in the presence of two witnesses.

JOSEPH M. REAMS.
